ABSTRACT

a plurality of printed information cards identifying informational units are positionable over a data processing card and each includes a slotted portion corresponding to one of the rows or columns on the card to facilitate registration of information on the data card by a conventional stylus. The slotted portion of the printed cards are staggered with respect to each other so that as each printed card is positioned over the data card for recording, a different row or column of the data card is exposed. A plastic template having a plurality of perforations corresponding to the scored portions on the data card is positioned over the card for indexing the stylus. A selector card is positioned over the template beneath the printed cards and selectively shields portions of the data card to prevent accidental or undesired recordings. A Styrofoam cleaning base supports the data card to facilitate positive indexing of the stylus and an enclosing container is provided which also aligns the data card, template and selector card into proper registration. The printed cards are hingedly connected to the enclosure to permit rapid and facile registration of each individual card for informational registration. Each card is detachable from the apparatus after it has been used to permit registration of the next card. A reversible mailer is provided to facilitate ease in sending and returning the apparatus through the mails.

PORTABLE CARD PUNCHING APPARATUS

BACKGROUND OF INVENTION

This invention relates to an apparatus for recording information on a machine processible card and, more particularly, to a portable device which provides easy and legible registration of the informational units.

With the advent of machine processible data cards such as the IBM punch card, information storage requiring voluminous files can now be reduced and stored on such a punch card which requires relatively insignificant storage space. Thus, seemingly, the use of such cards for manually recording data such as inventory, flow of inventory, surveys, voting cards, etc. would promulgate efficiency in the recording and storage of the desired information. This is true particularly where the machine-readable card can be coded at the "source" of the information sought without the necessity of an intermediate key punching step. However, one particular problem that has become apparent is that the benefit gained by the reduction in size of the data card has in part been set off by the reduction in size itself since it essentially eliminates legibly identifying each individual informational unit on the card itself. In addition, present proposals as illustrated by Harris, U.S. Pat. No. 3,201,038, issued Aug. 17, 1965, while overcoming some of the drawbacks indicated, remain relatively complex, cumbersome to handle and expensive.

SUMMARY OF INVENTION

It is a principal object of this invention to provide a portable card punching apparatus which is both simple to use and economical to construct.

Another object of the invention is to provide a device which is not only reusable, but can be easily altered for a variety of different types of uses and applications.

For achievement of these and other objects, this invention includes means for enclosing a penetrable base on which is supported a data processing card, a template to facilitate puncturing said card, a selector card for shielding portions of said template and data processing card and means for aligning said template and cards with respect to each other and said support. In addition, a plurality of printed cards conveying the informational units for registration are hingedly connected to one of said means for positioning each individual card over said selector card. Each card includes a slot which corresponds to one of the rows or columns on the data card when the card is positioned over the selector card. The individual slot on each card is staggered with respect to the other cards and slots so that as each card is positioned over the selector card for recording, a different row or column of the data card is exposed for registration of the informational units disclosed on said cards. The cards are detachably mounted to one of said means so that each card after use is removed to permit usage of the next card.

The apparatus permits easy insertion and removal of the data processing card, template, selector card and printed information cards to permit significant flexibility in the use and application of the apparatus.

Other objects and advantages of the invention will be made apparent in the following drawings and specification.

DESCRIPTION OF THE DRAWINGS

FIG. 1 is an exploded view showing the positional orientation of the selector card, template, data processing card and cleaning support means provided by this invention;

FIG. 2 is a side view of the apparatus shown in FIG. 3 with the hinge flap closed;

FIG. 3 is a perspective view of the apparatus of this invention;

FIG. 4 is a plan view of the apparatus with one of the printed informational cards in position for registration; and

FIG. 5 is a perspective view of the reusable mailer provided by this invention for sending and returning the apparatus by the mails.

DESCRIPTION OF THE PREFERRED EMBODIMENT

A portable card punching and information storing apparatus provided by this invention is shown and described in the context of a portable ballot casting apparatus which is mailed to the voter (such as an absentee ballot) and returned to the recorders office for recording along with the apparatus which can subsequently be reused. While for the sake of description, reference is made to a ballot apparatus, there is no intent to so limit the application of the invention as various and sundry applications are envisioned such as use of the apparatus for surveys, inventory records, examinations, and the like.

Referring now to the drawings in detail, a ballot card 10 is shown in the form of a conventional machine data processing card having a plurality of columns 12 arranged longitudinally with respect to the card. Each column includes a plurality of informational storage portions 14 which have a scored portion 16 which, when punched out, with a stylus or other pointed instrument, record the particular information related thereto. While data card 10 shown as a plurality of columns 12, laterally extending rows are equally susceptible to use in combination with a card. Thus, while the following description deals with a columnar relationship, it could apply to rows also.

Ballot card 10 is positioned over a support and cleaning base 20 as shown in FIG. 2, base 20 preferably being rigid to give bearing support when the ballot card is punched, but at the same time penetrable by both the stylus and the "punched out" card segment to permit facile punching of the individual tabs or scored portions 16. A support base comprised of Styrofoam provides the proper amount of rigidity and penetrability. In addition, it is extremely light for mailing and economical in terms of construction.

Ballot card 10 and support base 20 are enclosed in a box 22 (preferably cardboard for purposes of economy and weight) having a pair of closed sides 24, 26, ends 28, 30 and bottom 32. The top 34 is partially enclosed at 36, 38 and 40 having two dissimilar sized openings 42 and 44. Opening 42 is substantially larger than opening 44 and is defined between sides 24, 26 and top portions 36, 38. The area of the opening corresponds essentially to that portion of ballot card 10 having the plurality of columns and informational registering portions on it. The second opening 44 of top 34 is defined between sides 24, 26 and top portions 38, 40 and is provided to permit insertion of ballot card 10 beneath the top portions of the box so that it is positioned firmly on the Styrofoam base 20. Preferably, the Styrofoam base corresponds to the dimensions of the box and the ballot card 10 corresponds to the box's length and width so that when ballot card 10 is inserted through opening 44 into the box, it is inserted until its bottom end 46 (FIG. 2) abuts against end 30 of the box thereby indexing and positioning the ballot card properly within it. In addition, the card may be provided with one or more apertures 48 at the top thereof securable to suitable retainers on the unit to further position the card. Alternatively, a gummed seal or stamp may be affixed to the top of the card 10 and the member 40 to insure proper positioning of the card.

A template 50 is provided for positioning over ballot 10 and includes a plurality of frusto-conical perforations 52 corresponding to each of the portions 14 comprising columns 12 of the ballot. When properly aligned, the narrow sides of the perforations register immediately over tabs or scored portions 16 of the ballot card to facilitate proper puncturing of the tabs when the information is registered. Preferably, for purposes of weight and economy, template 50 is comprised of a rigid plastic. Thus, when a tab 14 is selected for punching to record the casting of a vote, a sharpened pencil or stylus is manipulated into the selected template perforation, guided to the proper location by the converging walls of the perforations and projected through the particular tab 14 into the Styrofoam base to record the vote. The base receives at least portions of the tab initially causing the stylus pressure to be concentrated on any non-severed portion of the segment to be punched out. The entire segment is thus separated from the

surrounding card, pushed into and retained by the support insuring a "clean" aperture for subsequent machine reading of the recorded information.

Preferably, template 50 is dimensionally designed so that when it is inserted above the ballot card in box 22, the bottom end 54 (FIG. 2) abuts end 30 of the box, its sides abut the sides of the box, and the upper end 56 abuts shoulder 45 formed by folding a section of member 42 cut away to form aperture or opening 44 downwardly upon itself and gluing the two members together. Shoulder 45, thus, will extend laterally the entire width of the unit and the template (and selector card to be discussed hereinafter) will be firmly positioned by abutment with end 30, sides 24 and 26 and shoulder 45.

In actual practice, since ballot card 10 is removed and replaced repeatedly for repeated voting, the ballot card is inserted in opening 44 beneath the template which remains in the box for the duration of the particular use intended. With the template in position, the fold forming shoulder 45 is preferably folded at opening 44 to facilitate the insertion of the ballot beneath the template. If the configuration of the ballot card or punching card is changed, then a different template will be used with perforations to match the different ballot card. In most instances, the configuration of the data processing card 10 and template 50 remain the same, regardless of the type of data being recorded. It is for this reason that a selector card 60 (described as follows) is used.

Selector card 60 is positioned over template 50 to shield that portion of the template and data card from being used for recording purposes in connection with a particular vote or application of the apparatus. Selector card 60 is comprised of an equal number of portions 62 corresponding to perforations 52 and portions 14 of the template and ballot respectively, portions 62 being arranged in similar rows or columns. However, only a selected number of portions 62 are punched out to form holes 64 to permit insertion of the stylus through the template to record the particular information desired. The reason for this is that generally, in a given application, only a selected number of tabs 16 are presented for puncture by a stylus to record the particular vote or registration of information. Thus, to eliminate accidental registration of undesired information which would interfere with the usage of the ballot card, selector card 60 is inserted over the template 50 and exposes only those perforations and tabs which are available for voting. Thus, selector card 60 shields the entire template and data card except for the pre-selected hole 64 punched in the card to correspond to the pre-selected portions 14 and tabs 16 to be used for the vote.

The length of selector card 60 is preferably designed so that the inner end 66 (FIG. 2) when it is inserted in box 22 abuts against end 30 of the box to align the selector card in registration over the template and data or ballot card 10. The upper end of the selector card should abut shoulder 45 (FIG. 2) and its width should equal the interior width of box 22 to firmly position it within the apparatus. Thus selector card 60 is preferably equal in size to template 50.

Referring now to FIG. 4, a printed card 70 bearing voting information is shown positioned over the apparatus to permit voting in accordance with the information thereon. The card includes a single slot 72 corresponding to a particular column of the ballot card and hence the template and selector card. Thus, when the informational bearing card is positioned and aligned over the apparatus, one of the columns 12 is exposed to the voter for purposes of casting a particular vote. For example, the card 70 shown in FIG. 4 is entitled a "straight party ticket" voting card permitting the voter if he chooses to cast a straight party ticket vote. The various parties are identified on vertical rows 74 with an arrow 76 pointing to the particular hole 64 exposing the template perforation and tab to be punctured to cast that particular vote. Thus, if the voter desired to vote straight Republican, he would inject the stylus or sharpened pencil into hole 64a to puncture and remove the particular tab positioned under the template. In essence, informational card 70 is a refined selector card in that it further

shields tabs available for voting by limiting the exposed tabs to one column, which particular column would correspond to a particular type of vote. Thus, with card 70 properly positioned, the voter is limited to voting in the particular example shown to a straight party ticket vote if so desired. Once a particular vote is cast, the card is removed and a different card is positioned for a different vote. Thus, in a typical political election, the first vote might be that as shown in FIG. 4 (a straight party ticket) with subsequent informational cards representing a vote for the Presidential and Vice-Presidential candidate, the gubernatorial candidate, etc.

In order to facilitate the handling of information cards and also their alignment and positioning over the selector card, template, and ballot respectively, a plurality of cards 70a, 70b and 70c (FIGS. 2 and 3) are hingedly mounted to the enclosure box 22 so that each individual information card can be manipulated into position over the voting apparatus. In order to provide simple and easy insertion of various information cards for use with the voting apparatus, the cards although larger than the selector card, template and ballot (in order to introduce legible writing pertaining to the vote) are provided with a flange or extended portion of reduced dimensions 78 corresponding dimensionally to end 30 of box 22. By providing a plurality of spaced holes 80 in extended portion 78 and in end 30 of the box, a metal clip 82 is removably inserted through the holes and folded over to secure the information cards to box 22. A crease 84 where extended portion 78 extends from card 70 is provided to permit easy rotation of the cards about hinge 84 into or out of position over the voting apparatus. Preferably, hinge or crease 84 is perforated to permit easy separation of the card 70 from the apparatus after the particular vote represented thereon has been cast.

The information card 70a nearest the voting apparatus is the first card positioned over the voting apparatus with cards 70b and 70c rotated counterclockwise (FIG. 2) onto the table or lap of the voter to expose the slot in and indicia on card 70a. After the vote relating to card 70a has been cast (or declined) the card is removed by tearing it away from the apparatus along the perforated hinge 84 and card 70b is next rotated clockwise (FIG. 2) into overlying position with respect to the selection card, etc. After the vote represented by card 70b has been cast (or declined) card 70c and subsequent cards are then used. While the apparatus in FIGS. 2 and 3 show three information cards 70a, 70b and 70c, it will be appreciated that any number or one could be used depending on the particular vote or application.

It should be pointed out, that the individual slot 72 on each information card 70 is laterally staggered or offset with respect to all other card slots, the lateral position of each such slot corresponding to one of the columns 12 on the ballot card. Thus, for each individual vote cast, a different column on the selector card, template and ballot card is exposed, each column pertaining to the particular vote being cast.

Referring briefly to FIG. 3, to facilitate easy insertion and removal of information cards into the apparatus, end 30 of box 22 has a lip portion 88 which is folded under the Styrofoam support base in the same fashion as a conventional carton is opened and closed. Thus, when all of the information cards have been used, end 30 is opened up and the metallic clasp 82 is opened to permit removal of the remaining extended portion 78, which are then discarded and a new set of vote information cards 70 are installed. It will be appreciated of course that if the voting apparatus as described is used for the casting of absentee ballots, the individual voter will cast his ballot and return the entire apparatus and ballot back to the recording office in charge of the vote at which point they will replace the apparatus with a fresh supply of vote information cards 70 and new ballot card 10.

In order to provide clear and legible printed indicia on printed cards 70 to identify the candidates or other informational units, cards 70 (70a, 70b, 70c, etc.) are preferably wider than the selector card, template and ballot. In the embodiment shown, cards 70 are equal to each other in width so that a uniform print can be used which is legible.

Since the vote information cards 70 are somewhat larger than the width of the selector card, template and ballot card and support enclosing box 22, an outer box 90 (shown in FIG. 1) is included for providing complete support on the entire face of the individual vote information cards 70. To achieve this, box 90 (corresponding essentially to the length of box 22) includes a pair of closed sides 92, 94; ends 96, 98; and bottom 100. Two lateral support portions 102, 104 provide the requisite support for the extended portions of the vote information cards with the interior recess 106 permitting insertion of the apparatus as shown in FIG. 3 to be installed in box 90 providing a smooth flush supportable voting apparatus.

Outer box 90 functions additionally to stabilize the interior components. The lateral supports 102 and 104 with their depending sides function, for example, to retain the inner box 22 and the components contained therein in proper geometric configuration despite the use of rather flexible and inexpensive material. To this end, support portions 102 and 104 preferably comprise closed, rectangular tubes of cardboard suitably secured along the edges of box 90. The ends 96 and 98 of box 90, similarly, function to hold the flaps of interior box 22 in closed position, further assuring proper registry of all components.

A reusable mailing carton 110 is provided with a window 112 for exposing the senders or addressee's address attached or stamped on box 90. Preferably, the senders address (in this case the address of the recorders office) is permanently stamped on the bottom 100 of box 90 so that it is exposed through window 112 when positioned properly therein. The addressee's address is applied by label in the reciprocal position on bottom 100 so that after the voter casts his votes, he reinserts the entire voting apparatus in reciprocal fashion to that received so that the recorders office address may be shown.

OPERATION

To operate the apparatus, the office administering the vote positions a fresh ballot card beneath the inserted template and selector card for use in the particular election to be administered. The proper voting information cards 70 (70a, 70b and 70c) are then affixed to end 30 of box 22, the entire apparatus being inserted in box 90. The device is then inserted in mailer carton 110 and mailed to the particular voter. The voter takes a sharpened pencil or enclosed stylus, takes the device out of the mailer carton and rotates vote information cards 70c and 70b out away from card 70a already in position for voting. The voter then casts his vote (or declines) pertaining to card 70a and detaches the card by tearing along the perforated crease 84. Card 70b is then positioned for loading and the process is repeated until all of the particular cards supplied have been detached. After this, the device is inserted back in the mailer carton 110 with the recorders office official address exposed in window 112 and the ballot and card punching apparatus is returned for reuse by the administering office. The combination of the selector card and staggered slots on each individual vote information card prevents accidental registration of undesired information other than that provided for selection by the individual voter.

The entire apparatus is comprised of paper, cardboard, plastic and Styrofoam, all economically attractive materials and yet the speed, efficiency and reusability features additionally provide a package which is both legible to the user and feasible to the supplier. The invention also lends itself readily to fabrication from more durable components depending upon the particular use to which it is put.

Although but one embodiment has been shown and described, it will be obvious to those having ordinary skill in this art that the details of construction may be modified in a great many ways without departing from the unique concepts presented. It is therefore intended that the invention is limited only by the scope of the appended claims rather than by particular details of construction shown, except as specifically stated in the claims.

The embodiments of the invention in which an exclusive property or privilege is claimed are defined as follows.

1. Apparatus for manually recording information on a machine processible punch card having a plurality of scored tab portions arranged in columns or rows for selective perforation, said apparatus comprising, in combination:

support means for supporting said punch card;

10 a template positioned over said punch card and having a plurality of arranged perforations for indexing the insertion of a recording tool to perforate said scored portions; a selector card positioned over said template to shield selected perforations and tab portions and having a plurality of openings, said openings being aligned with those of said perforations and scored portions selected for possible recording;

15 a printed information card positioned over said selector card and having a slot corresponding to one of said columns or rows to permit recording selected informational units on said punch card and shield the remaining columns or rows, said printed card including printed indicia on the face thereof identifying the individual informational units being recorded;

20 and means for positioning said punch card, template, selector card and printed card with respect to each other and said support means so that said scored portions, perforations, openings and slot are properly aligned for use with said recording tool.

9. The combination according to claim 6 wherein the top portion of said box means between said first and second openings includes a shoulder portion on the interior side thereof, said template and selector card being dimensionally equal in length to the distance between said shoulder and the end of said box on the other side of said second opening and equal in width to said box so that when said selector card and template are positioned above said support means, they are indexed and secured for recording.

10. The combination according to claim 6 wherein said printed information card is substantially greater in width than said selector card, template, punch card, support means and box-like means so that said printed indicia thereon is legible with respect to the selected informational units being recorded, and said means for positioning is further characterized as comprising a second box-like means having two sides, two ends, and a bottom, said second box-like means including a recessed portion for receipt of said first box-like means to facilitate the alignment of said cards and template, said second box-like means including a top portion adjacent each side of said recessed portion to support the extended width of said printed information cards.

11. Apparatus for manually recording information on a machine processible punch card having a plurality of scored tab portions arranged in columns or rows for selective perforation, said apparatus comprising, in combination:

support means for supporting said punch cards;
a template positioned over said punch card and having a plurality of arranged perforations for indexing the insertion of a recording tool to perforate said scored portions; a plurality of printed information cards hingedly mounted to said apparatus for rotation into position over said template to shield selected perforations and tab portions, said cards having a plurality of openings, said openings being aligned with those of said perforations and scored portions selected for possible recordings when said cards are positioned over said template for recording, said printed cards including printed indicia on the face thereof identifying the individual informational units being recorded, said printed cards including means for detaching them with respect to said apparatus so that after each of said cards is positioned in said recording position for use, it is removed to permit the next card to be positioned for recording;
and means for positioning said punch card, template and printed information card with respect to each other and said support means so that said scored portions, perforations, and openings are properly aligned for use with said recording tool.

12. The combination according to claim 11 wherein said means for detaching said printed cards is comprised of a perforated fold along a portion of said cards to permit tearing said cards away from said apparatus after use.

13. The combination according to claim 11 wherein said combination is further characterized as including a selector card positioned over said template to shield selected portions and tab portions and having a plurality of openings, said

openings being aligned with those of said perforations and scored portions selected for possible recording; and each of said printed card openings forming a slot corresponding to one of said columns or rows to permit recording selected informational units on said punch card and shield the remaining columns or rows, each of said slots being staggered with respect to each other when positioned for recording so that each printed card when used, records information on a different column or row.

14. The combination according to claim 13 wherein said support means is both rigid and penetrable to facilitate the insertion of said recording tool through a selected printed card slot, selector card opening, template perforation and punch card scored tab portion to record an informational unit, said support means being rigid to provide a solid resistance to said tab portion so that the entire tab is severed from the punch card and penetrable to permit injection of said tool and tab into said support means to provide a clean severance of said tab.

15. The combination according to claim 14 wherein said support means is comprised of expanded polystyrene.

16. The combination according to claim 13 wherein said means for positioning is comprised of a box-like means having two sides, two ends, a bottom and a top for enclosing said support means, said top having first and second openings, said first opening permitting insertion of said punch card beneath said top and above said support means, said second opening exposing said columns or rows of scored tab portions for recording, said second opening further permitting insertion of said template and selector card respectively over said punch card and support means.

17. The combination according to claim 16 wherein the top portion of said box means between said first and second openings includes a shoulder portion on the interior side thereof, said template and selector card being dimensionally equal in length to the distance between said shoulder and the end of said box on the other side of said second opening and equal in width to said box so that when said selector card and template are positioned above said support means, they are indexed and secured for recording.

18. The combination according to claim 16 wherein said printed information card is substantially greater in width than said selector card, template, punch card, support means and box-like means so that said printed indicia thereon is legible with respect to the selected informational units being recorded, and said means for positioning is further characterized as comprising a second box-like means having two sides, two ends, and a bottom, said second box-like means including a recessed portion for receipt of said first box-like means to facilitate the alignment of said cards and template, said second box-like means including a top portion adjacent each side of said recessed portion to support the extended width of said printed information cards.

19. The combination according to claim 18 wherein said printed cards are dimensionally equal to permit said legible printed indicia thereon to be uniform in size.
